UNITED STATES PATENT OFFICE.

OTTO FORSTER, OF BALTIMORE, MARYLAND.

BAR-FIXTURE.

No. 904,253.

Specification of Letters Patent.

Patented Nov. 17, 1908.

Application filed May 11, 1908. Serial No. 432,207.

To all whom it may concern:

Be it known that I, OTTO FORSTER, a citizen of the United States, residing at Baltimore, in the State of Maryland, have invented 5 certain Improvements in Bar-Fixtures, of which the following is a full and complete specification.

My invention is an improvement in store-furniture, and has particular reference to 10 what may be termed a bar-fixture or counter especially adapted for use in restaurants or bar-rooms.

The principal objects of my invention are to provide a bar for restaurants or bar-rooms 15 which shall be attractive in appearance, and in which the parts constituting the fixture as a whole are so constructed and arranged as to economize space and make it more convenient for the bar-tender to wait upon his 20 customers.

With these principal objects in view my invention consists in making the bar or fixture circular in shape or in the form of a large barrel with a surrounding counter, and 25 furnishing the interior of the same with certain devices or appliances of peculiar construction; all as hereinafter fully described and claimed.

In the accompanying drawings, which 30 form a part of this specification:—Figure 1 is a front elevation of a bar or bar-room fixture, constructed in accordance with my invention. Fig. 2 is a vertical sectional view. Fig. 3 is a transverse sectional view. Fig. 4 35 is a detail view illustrating the application of an attachment for use by a cashier. Fig. 5 is a detail of a panel and strip with which it engages.

Like numerals of reference indicate like 40 parts in all the figures of the drawings.

In carrying out my invention the body portion or framework of the bar is constructed in the form of a large barrel either round or oval-shaped, comprising the vertical staves 5, which are connected at top and bottom to the heads 6 and 7, respectively, and the structure braced or reinforced by metal bands or hoops 8 near each end. In 45 the present instance the upper head 6 of the barrel forms the ceiling of the bar or fixture, while the lower head 7 forms the floor, and the circular wall formed by the staves is bulged outward to the same extent as is customary in the ordinary form of whisky 50 barrel.

At a suitable distance from the bottom end

of the bar or fixture, and extending horizontally around the same, is a counter 9, which may have either a plain top surface or provided at its front edge with a bead, as 10. 60 The counter projects a suitable distance from the body of the fixture, and is supported by brackets 11. At one side of the frame the counter is provided with a hinged section 9^a, which is adapted to fold down, as shown in 65 Fig. 3.

Directly above the counter the barrel-shaped fixture or bar is provided with several openings, as shown, which are finished off around the edges with ornamental molding strips, as 13, the said openings being of suitable size so that the bartender who is standing within the bar may serve the 70 customers standing on the outside. The vertical walls 14 between the openings are each 75 provided on its inner side with vertical strips 15, which are grooved at one edge, as at 16, to receive certain removable devices hereinafter described, said strips having openings 17 through which lugs on the removable devices pass. The strips are provided with holes through which removable attaching screws 18 pass.

In some instances, as when the device is placed against a wall, one or more of the 80 openings towards the wall may be closed. In Fig. 1 I have shown this application of the device, in which three of the openings in the rear are closed. These are closed by panels 19, in the form of mirrors, and between 85 the mirrors are shelves 20, upon which may be placed glasses, liquor-bottles, and other articles. Each shelf and its supporting bracket 21 may be, and preferably is, formed integrally with its supporting panel-frame, 90 and said panel-frame is provided at its four corners with lugs 19^a adapted to pass through the openings 17 of the supporting strips 15 and engage the groove, said openings being so located that the lugs will rest 95 in the grooves below the same.

The counter extends within the frame or bar a suitable distance, as shown, and below the counter at one side of the bar is a cabinet comprising drawers 22 and closets 23. 100 At the other side of the bar is an ice-chest through the front wall of which pass beer faucets 24, and in addition to these other bar appliances may be provided.

As shown in Fig. 4 of the drawings, one 110 of the removable panels may be in the form of a cashier's screen, as 25, adapted to fit the

lower part of one of the openings, and provide the usual cash-opening and shelf, and alongside of this panel may be arranged an ordinary cash-register.

5 Within the barrel-shaped frame, and upon the bottom thereof, is a stand 26, providing shelves on which may be supported the usual articles forming the complement of a bar. This stand is preferably located at the center 10 of the bar, so that the bar-tender may pass around the same.

As will be readily seen I provide a bar which is not only attractive in appearance, but will also provide a very useful and convenient fixture for a restaurant or bar-room, 15 inasmuch as a bar-tender stationed therein may readily and conveniently serve a large number of customers.

In some instances, for instance for a large 20 trade, the device would be placed in the center of a restaurant or bar-room, and in this instance none of the openings would be closed, so that customers could be served all around the device. On the other hand, for 25 a small trade, or for lack of space, the device may be placed against a wall, and in this instance the openings towards the wall would be closed by the panels and shelves and thereby provide supports for glasses, bottles, and 30 other articles, and the folding section of the counter swung down.

Having thus described my invention, I claim:

1. In a store-fixture or bar, a barrel-shaped frame having spaced apart openings 35 therein, a counter surrounding the barrel-shaped frame at the lower end of the openings and extending within said frame, a cabinet and bar-fixtures within the frame 40 below the counter, retaining strips at the inner side of the frame between the openings, and removable panels adapted to be engaged by said strips, as herein shown and described.

45 2. In a store-fixture or bar, a barrel-shaped frame comprising a top, a bottom, and a circular wall, the latter being bulged outward, said barrel-shaped frame having openings in the circular wall, a counter sur-

rounding the frame below the openings and 50 having a folding section at one side of said frame, a cabinet and bar-fixtures within the frame below the counter, vertical strips removably attached to the inner side of the frame between the openings, and removable 55 panels adapted to be engaged by said strips, as shown and described.

3. In a store-fixture or bar, a barrel-shaped frame comprising a top, a bottom and a circular wall, the latter being bulged 60 outward, said barrel-shaped frame having openings in the circular wall, a counter surrounding the frame at the lower end of the openings and extending into said frame through the openings, a folding section on 65 the counter at one side of the frame, vertical strips detachably secured to the inner side of the frame between the openings therein, panels removably engaging the strips, and shelves forming an integral part 70 of the panels; together with a stand located on the bottom of the frame at the center thereof, as herein shown and for the purpose set forth.

4. In a store-fixture or bar, a round or 75 oval-shaped frame comprising a top, a bottom, and a circular wall, the latter being bulged outward and having openings therein, a counter surrounding the frame at the lower end of the openings and extending 80 into said frame through said openings, a folding section of the counter at one side of the frame, vertical strips detachably secured to the inner side of the frame between the openings therein and having vertical grooves 85 16 and openings 17, panels having lugs at 16 its corners adapted to pass through the openings and engage the grooves, and a shelf forming a part of each panel, as herein shown and described. 90

In testimony whereof I have signed my name to this specification in the presence of two subscribing witnesses.

OTTO FORSTER.
